UNITED STATES PATENT OFFICE.

GEORGE WILLIAM FRANK, JR., AND FREDRICK CARLOCK, OF JERSEY CITY, NEW JERSEY, ASSIGNEES TO THEMSELVES AND GEORGE WILLIAM FRANK, SR., OF JERSEY CITY, NEW JERSEY.

BURGLAR ALARM.

1,426,169.

Specification of Letters Patent. Patented Aug. 15, 1922.

Application filed August 25, 1921. Serial No. 495,437.

To all whom it may concern:

Be it known that we, GEORGE WILLIAM FRANK, Jr., and FREDRICK CARLOCK, citizens of the United States, and residents of Jersey City, Hudson county, and State of New Jersey, have invented certain new and useful Improvements in Burglar Alarms, of which the following is a specification.

Our invention relates to that class of burglar alarms in which the opening or closing of a door or window closes an electrical circuit, in which an alarm or other signalling device is interposed, and the invention consists in the special arrangement and construction of parts hereinafter described and claimed.

In the accompanying drawings,

Fig. 1, is a front elevation of our device applied to the inside casing of a door, the electric circuit, battery and signalling device, being shown in diagram;

Fig. 2, is a side elevation partly in section, upon an enlarged scale, showing the bolt holding the contact spring out of engagement with the adjustable stop;

Fig. 3, is a front elevation of the parts shown in Fig. 2;

Fig. 4, is a side elevation of the device, the parts having been "set" by the arm upon the door being closed;

Fig. 5, a similar view, showing the spring bolt engaging the upper end of the contact spring, for the purpose of allowing a person to leave the room and close the door after them;

Fig. 6, a similar view showing the parts in the position they assume after the door has been tampered with or opened.

Our improved device A, consists of the back plate a, having the lower and upper lugs or projections a', a'', provided with screw holes a³, a⁴, by means of which it may be attached by screws to the door casing C.

This back plate a, is formed near its upper end with an elongated lug or projection L, having holes or recesses l, l' for the reception of the locking bolt B, and the spring bolt B'. A chain c, may be attached to the shoulder b, formed upon the upper end of the bolt B, for the purpose of preventing the said bolt from becoming lost or misplaced.

The shoulder b, formed on the upper end of the locking bolt B, acts as a stop when in contact with the upper surface of the lug L,

and prevents the bolt B, from dropping through the recess l.

The spring bolt B', is formed at its lower end with a shoulder b², and at its upper end with a head or shoulder b³, between which and the upper side of the lug L, a tension spring T, is interposed. The lower surface of the lug L, is formed with a recess l³, for the reception of the shoulder b², when the spring bolt assumes its normal position.

Attached to and forming part of the back plate a, at its lower end, extends a bracket A', in which rests an adjustable contact P.

This contact P, is formed with a screw thread p, which engages a female screw 70 thread formed in the bracket A', and by which it may be regulated with relation to the contact spring S.

To the lower inside face of the back plate a, is attached a contact spring S, which is 75 insulated therefrom by the insulation I.

The parts being in the position shown in Fig. 1, of the drawings, the door D, being closed and having attached thereto the arm d, which acts as a circuit closer and breaker, 80 the device A, being interposed in an electrical circuit by means of the wires w, w, having a battery R, and signalling device G. The operation is as follows:—

When it is desired to set the device, the 85 parts being in the position shown in Fig. 4, the door D, being closed, the arm d, thereon bears against the contact spring S, and forces and holds said contact spring S, away from the adjustable contact P, (the adjustable contact P, having been adjusted with relation to the contact spring S), the lower end of the locking bolt B, rests upon the upper bent end or shoulder s', of the contact spring S.

When the door D, is opened or tampered with, the arm d, immediately releases the contact spring S, said contact spring S engaging with the adjustable contact P, and forming an electrical circuit and setting 100 the signalling mechanism in operation, and at the same time, the locking bolt B, drops down and between the back plate a and the rear side of the contact spring S, (see Fig. 6) thereby locking the parts and preventing 105 the breaking of the electrical circuit, until the parts have been again restored to their normal positions.

When it is desired to set the device by a person leaving the room or premises, and 110

wishing to close the door after them, the 5
spring bolt B' , is pressed downward in the
lug L , with its shoulder b^2 , protruding from
the recess b^3 , formed in the lower surface of
the lug L , and the upper end of the tension
spring S , being formed with a catch or
hook s' , is brought in contact therewith and
held thereon, and at the same time this
shoulder s' , holds the locking nut B , in po-
10 sition with relation to the contact spring S ,
as shown in Fig. 5, of the drawings.

Upon the door D , being again closed, its
arm d , will again force the shoulder s' , on
the contact spring S , out of engagement with
15 the shoulder b^2 , on the spring bolt B' , and
allow said spring bolt B' , to return to its
normal position. The parts are now set and
ready for operation.

If it is desired to prevent the device from
20 being in continual operation, the spring S ,
may be held out of contact by the bolt B ,
as shown in Fig. 2, and so held until it is
desired to renew the operation of signalling.

What we claim as our invention and de-
25 sire to secure by Letters Patent is,

1. In a device of the character designated,
the combination of a back plate formed with
a projecting lug having a recess for the re-
ception of a locking bolt, said locking bolt
30 formed with a shoulder, a spring bolt rest-
ing in said lug, formed with a shoulder on
its lower end, a spring contact attached to
said back plate, but insulated therefrom, said

spring contact formed at its upper end with
a shoulder for engagement with the shoul-
der on the spring bolt, a bracket formed
35 on said back plate, and projecting there-
from, and an adjustable contact mounted
thereon, for the purpose described.

2. In a device of the character designated, 40
the combination of a back plate formed with
a lug or projection having a recess formed
therein for the reception of a locking bolt
formed with a shoulder upon its upper end,
a spring bolt resting in said lug, formed 45
with a shoulder upon its lower end, and
said spring bolt having a spring inter-
posed between the upper surface of the lug
and a head formed upon the upper end of
said spring bolt, a spring contact, attached 50
to said back plate but insulated therefrom,
said spring contact formed with a shoulder
at its upper end for engagement with the
shoulder on the end of the spring contact,
a bracket formed on said back plate and 55
projecting therefrom, an adjustable contact
mounted in said bracket, said back plate
formed with lugs at its upper and lower
end, said lugs being formed with perfora-
tions for the purpose described.

GEORGE WILLIAM FRANK, JR.
FREDRICK CARLOCK.
